REVAPORIZER

Loyd J. White, San Antonio, Tex., assignor to
 Southern Steel Company, a corporation of
 Texas

Application August 26, 1936, Serial No. 98,047.

7 Claims. (Cl. 62—1)

This invention relates to liquefied gas systems for household use and, among other objects, aims to provide a more efficient system by providing means to revaporize any gas which may have condensed after leaving the storage tank and before it reaches the household gas appliances.

In the drawing:

Fig. 1 is a sectional view showing a liquefied gas system for household use;

Fig. 2 is an enlarged vertical sectional view taken through the lower end of the revaporizing unit; and

Fig. 3 is a sectional view taken on the line 3—3 of Fig. 2.

In accordance with the invention, the improved revaporizer is adapted for use in any liquefied gas system, more particularly in connection with the dispensing apparatus disclosed in my copending application, Ser. No. 98,048, filed August 26, 1936.

Referring more particularly to the drawing, there is shown a well known commercial liquefied gas system comprising a storage tank 10 buried in the ground and from which vaporized gas is delivered through an underground main or conduit, herein shown as being composed of substantially horizontal and vertical pipes 11 and 12 leading to the various gas appliances within a house 13. The liquefied gas is stored under pressure in the tank 10 and is vaporized in the tank. It is adapted to be delivered from the tank through a standpipe 14, nipple 15, thence, downwardly through valve 16, a pressure reducing valve controlled by a pressure regulator 17, and through the main 11. The usual low pressure relief valve 18 is provided on the low pressure side of the regulator 17 and both the valve 18 and regulator are connected to a vent pipe 19. The above controls are all clearly shown and described in the aforesaid application.

Heretofore, it has been the custom to provide only the pipes 11 and 12 leading into the house. However, it has been found that some of the vaporized gas in pipe 11 condenses, especially in cold weather and in cold climates. The condensate is trapped in the lowest part of the main and, when a valve of the gas appliance in the house is opened, the vaporized gas from the tank bubbles through the trapped condensate, causing a fluctuation of the pressure at the appliance. To overcome this objection, the present invention provides means to revaporize the condensate in the main by utilizing the heat of the earth.

Herein, the lowest point of the main is the juncture of the pipes 11 and 12 and at this point, an ordinary T 20 is provided, so that the re-

vaporizing unit may be connected thereto. The unit is shown as comprising a vertically arranged pipe 21 screw threaded into the lower opening in the T and extending downwardly into the ground well below the maximum frost line. The lower end of the pipe 21 is closed and pointed as indicated at 22 so that it may be driven into the ground where the character of the soil permits. Any condensate forming in the pipes 11 and 12 will, due to the inclination of the pipe 11, drain 10 into the pipe 21 where it will be revaporized by absorbing heat from the surrounding earth.

To increase the heat exchanging surface of the pipe 21, radial fins 23 are secured to or formed on the pipe, the fins preferably extending nearly the full length of the pipe. The pipe 12 is shown as being surrounded with heat insulating material 24 between the ground level and the bottom of the house to protect the pipe from freezing and to prevent recondensation of the gas at this point.

At the upper end of the pipe 12 and within the house, there is shown an ordinary T 25 having a short lateral nipple 26 leading to a suitable cut off valve 27 from which a pipe 28 leads to 25 the various gas appliances. The upper branch of the T 25 normally is closed by an ordinary screw plug 29 which, however, may be removed so that any condensate from a poor grade of fuel which will not revaporize in cold weather can be 30 pumped out of the main.

It is to be noted that the low pressure relief valve 18 in connection with the pressure regulator 17 relieves the house service main of any excess pressure which might develop as a result of revaporizing condensate in the heat exchanger 21 faster than the house appliances can consume revaporized gas.

From the foregoing description, it will be seen that the efficiency of a liquefied gas system has 40 been greatly increased by the addition of the revaporizing unit. It is relatively simple and the cost of installation is very small.

Obviously, the present invention is not restricted to the particular embodiment thereof 45 herein shown and described. Moreover, it is not indispensable that all the features of the invention be used conjointly, since they may be employed advantageously in various combinations and sub-combinations.

What is claimed is:

1. A liquefied gas system of the class described comprising, in combination, a storage tank adapted to dispense vaporized gas; a service main for the vaporized gas connected to and 55

leading from the tank; and heat exchanging means connected to the lowest point of the service main and extending into the ground to vaporize any condensate in the service main by utilizing 5 the heat from the earth.

2. A liquefied gas system of the class described comprising, in combination, a storage tank adapted to dispense vaporized gas; a service main for the vaporized gas connected to and 10 leading from the tank; and a heat exchanger connected to the lowest point of the main and extending into the ground below the maximum frost line, said heat exchanger being closed at its lower end.

15 3. A liquefied gas system of the class described comprising, in combination, a storage tank adapted to dispense vaporized gas; a service main for the vaporized gas connected to and leading from the tank; a heat exchanging pipe 20 connected to the lowest point of the main and extending into the ground below the maximum frost line, said pipe being closed at its lower end; and radial fins on the pipe extending longitudinally thereof.

25 4. In a liquefied gas system of the class described, a storage tank; a service main connected to and adapted to carry vaporized gas from the tank; a pipe T having a lateral branch connected to the end of the main remote from the 30 tank and having upper and lower branch openings; a pipe connected to the lower opening and extending into the ground below the maximum frost line, said pipe being closed and pointed at its lower end; a second pipe extending upwardly 35 from the upper branch of the T; a second pipe T having a lower opening connected to the upper end of the second pipe, said second T also having a lateral and an upper branch opening; a valved pipe connected to the lateral branch opening of 40 the second T; and a clean-out pipe plug in the upper branch opening of the second T.

5. In a liquefied gas system of the class described, a storage tank; a service main connected to and adapted to carry vaporized gas from the tank; a pipe T having a lateral branch connected to the end of the main remote from the 5 tank and having upper and lower branch openings; a pipe connected to the lower opening and extending into the ground below the maximum frost line, said pipe being closed and pointed at its lower end; and a second pipe extending upwardly from the upper branch of the T. 10

6. In a liquefied gas system of the class described, a storage tank; a service main connected to and adapted to carry vaporized gas from the tank; a pipe T having a lateral branch connected to the end of the main remote from the 15 tank and having upper and lower branch openings; a pipe connected to the lower opening and extending into the ground below the maximum frost line, said pipe being closed and pointed at 20 its lower end; radial fins on the pipe and extending longitudinally thereof; and a second pipe connected to the upper branch of the T and leading upwardly therefrom.

7. In a liquefied gas system of the class described, a storage tank; a service main connected to and adapted to carry vaporized gas from the tank; a pipe T having a lateral branch connected to the end of the main remote from the tank and having upper and lower branch openings; a pipe connected to the lower opening and extending into the ground below the maximum frost line, said pipe being closed and pointed at 30 its lower end; a second pipe extending upwardly from the upper branch of the T; a removable 35 closure at the upper end of said second pipe; and a valved conduit connected to the second pipe near its upper end.
